UNITED STATES PATENT OFFICE.

ROBERT H. MILAM, OF HELENA, ARKANSAS, ASSIGNOR TO LONG STAPLE COTTON GIN
MANUFACTURING COMPANY, OF HELENA, ARKANSAS.

COTTON-GIN.

1,367,491.

Specification of Letters Patent.

Patented Feb. 1, 1921.

Application filed March 18, 1920. Serial No. 366,797.

To all whom it may concern:

Be it known that I, ROBERT H. MILAM, a citizen of the United States, residing at Helena, in the county of Phillips and State 5 of Arkansas, have invented a new and useful Cotton-Gin, of which the following is a specification.

This invention relates to ginning machines, and it is the main object of the invention to provide means to permit of a 10 free and unobstructed passage of the cotton from the roll box, to the doffer, thus eliminating the possibility of the long staple cotton becoming broken, in its passage from 15 the roll box.

A further object of the invention is to provide a clearance between the upper ends of the ribs, and the lower edge of the rear wall of the roll box to permit the cotton to 20 pass therefrom, the seeds being removed by their contact with the lower edge of the rear wall of the roll box.

With the foregoing and other objects in view which will appear as the description 25 proceeds, the invention resides in the combination and arrangements of parts and in the details of construction hereinafter described and claimed, it being understood that changes in the precise embodiment of 30 the invention herein disclosed, may be made within the scope of what is claimed, without departing from the spirit of the invention.

Referring to the drawing:—

35 Figure 1 illustrates a vertical section through a cotton gin constructed in accordance with the present invention, and

Fig. 2 illustrates a fragmental front elevational view, the same being partly broken 40 away to illustrate the clearance formed between the upper ends of the ribs, and the roll box.

Referring to the drawing in detail, the reference character 5 designates the rear 45 wall of the frame of the machine which extends upwardly terminating at a point an appreciable distance above the upper edge of the gin saws indicated at 6, and as shown, the upper end of the rear wall supports the 50 rear wall 7 of the roll box.

The gin saws 6 are arranged in spaced relation with each other in the usual manner,

the same being supported on the power shaft 8, which is shown as extending through the saw, the shaft being keyed or otherwise secured to the saws 6, so that rotary movement of the shaft produces a relative movement of the gin saws.

An angular supporting bar 9 forms a part of the gin frame, and this bar 9 supports a 60 securing bar 10, to which the lower ends of the ribs 11 are secured, by means of the screws 12 passing through suitable openings provided in one end of each of the ribs.

The front wall 13 of the roll box is curved 65 in the usual manner, the lower edge of which has connection with the securing beam 14 in any suitable manner, which beam 14 also provides means for supporting the upper portion of the ribs 11, the 70 ribs 11 being shown as having connection with the beam 14 through the lateral extensions 15, which form a part of each of the ribs.

Forming a part of each of the ribs, are 75 lateral ribs 16 which extend from a point adjacent to the upper end of each of the ribs, the upper end terminating at a point adjacent to the base of the teeth of the saws, and coöperate with the lower edge 17 of the 80 roll box, to provide a clearance 18 to permit the cotton to have an unobstructed passage from the roll box to the doffer.

In the operation of the device, cotton is carried into the roll box, in the usual manner, where the same is caused to revolve within the roll box, the saws bringing the cotton through the clearance between the upper ends of the ribs 11 and the lower edge of the rear wall of the roll box, the 90 lower edge 19 contacting with the seeds to dislodge the same from the cotton, where the seed pass on to the lateral rib 16, and are carried off in the usual manner.

From the foregoing it will be seen that 95 long staple cotton is carried through the space between the upper ends of the ribs and roll box to the end that the same is unbroken and free of seed.

Having thus described the invention, 100 what I claim as new is:—

In a cotton gin, a frame, a roll box supported by the frame, a plurality of gin saws operating under the roll box, a plu-

rality of ribs disposed between the saws, each of said ribs having a lateral extension providing means to secure the ribs to the roll box, and said ribs being constructed to provide a clearance between the upper ends thereof and the roll box, to permit the passage of cotton from the roll box.

In testimony that I claim the foregoing as my own, I have hereto affixed my signature in the presence of two witnesses.

ROBERT H. MILAM.
